UNITED STATES PATENT OFFICE.

TAKVOR BARDEZBANIAN, OF NEW YORK, N. Y.

DESIGN FOR A BREAD-BOARD.

42,117.

Specification for Design.

Patented Jan. 30, 1912.

Application filed November 23, 1910. Serial No. 593,974. Term of patent 7 years.

To all whom it may concern:

Be it known that I, TAKVOR BARDEZBANIAN, a subject of the Sultan of Turkey, residing at New York city, in the county of New York and State of New York, have invented a new, original, and ornamental Design for a Bread-Board, of which the following is a specification, reference being had to the accompanying drawing, forming part thereof.

The figure is a plan view of a bread board, showing my new design.

I claim:

The ornamental design for a bread board, as shown.

TAKVOR BARDEZBANIAN.

Witnesses:

LAURA E. SMITH,
FREDK. F. SCHUETZ.
